UNITED STATES PATENT OFFICE

RALPH H. LANGLEY AND JULIUS K. DREXELIUS, OF CINCINNATI, OHIO, ASSIGNORS TO
THE CROSLEY RADIO CORPORATION, OF CINCINNATI, OHIO, A CORPORATION OF OHIO

CONTROLLING AND INDICATING DEVICE FOR RADIO SETS

Application filed July 11, 1930. Serial No. 467,276.

Our invention relates to controlling means for radio sets, particularly such means as are used to operate rotor shafts of variable condensers or the like, and particularly controlling means which are equipped with visual indicators which may be electrically illuminated.

Objects of our invention are the provision of controlling and indicating means which are simple of construction and not liable to de-arrangement and which represent economies in construction.

Another object of our invention is the provision of indicating means which are connected positively to the shaft of the variable condenser or like mechanism being actuated, so as to give an induction which is at all times correct, and which is not subject to displacement so as to give a false reading, as are bands and the like.

Still another object of our invention is to combine such means with vernier actuating means for the control shaft and to provide such an interrelation of parts that a movement of the knob of the vernier actuating shaft will produce a movement of the indicating means in the expectant direction, so that the user is not in doubt as to which direction the knob should be turned.

Still another object of our invention is to provide a construction in which the visual indicator may be placed quite close to the knob or other device which actuates the vernier mechanism, which has advantage in the construction of radio sets.

Still another object of our invention is to provide indicating means in which the dial is readily visible to the operator, and is so disposed as to be conveniently illuminated by an electric light otherwise concealed within the cabinet or frame of the device and a mechanical arrangement of the operating parts to this end.

A further object is the attainment of the foregoing objects in a type of construction in which the condenser gang or other controlled device may be located with its shaft substantially perpendicular to the front panel of the frame or cabinet of the radio set.

These and other objects of our invention

which will be set forth hereinafter or will be apparent to one skilled in the art upon reading these specifications, we accomplish by that certain construction and arrangement of parts of which we shall now describe a preferred embodiment, reference being made to the drawings which form a part thereof.

In the drawings:—

Figure 1 is a view partly in side elevation and partly in vertical section on the line 1, 1 of Fig. 2, of a device embodying our invention, and also showing part of a condenser gang controlled thereby.

Fig. 2 is a front elevation of the device.

Fig. 3 is a perspective detail of the dial.

Fig. 4 is a perspective detail of the face plate.

We have shown a condenser gang of a commercial type, having a series of rotor and stator plates indicated generally at 1 and enclosed in a casing 2. A central operating shaft 3 to which the rotor plates are attached, is provided, and it is to this shaft that our controlling and indicating means is applied. It will be understood that our control indicating means is applicable to other devices besides condensers, the condenser gang being shown in this case is illustrative merely of its application.

A device to be controlled, as exemplified by the condenser gang, will be understood as mounted upon a suitable base or frame in a radio set or other mechanism. To the rotor shaft we attach operating means and actuating means, and we provide as a part of the operating means, an indicator chart or dial. In the exemplary embodiment shown we have provided a flanged collar 4 on the rotor shaft, to which, as by means of rivets 5 or the like, we attach an operating device comprising a disc 6, to which disc is attached means for affecting the rotation of a shaft, such means may be any desired, such, for example, as gearing; but in the embodiment of the drawings we have provided a drum member which is driven from a pulley or spool on the actuator shaft by a belt, band, cable or other power transmitting device, as will hereinafter be described. We prefer to make the drum and indicating dial in one piece

by a stamping, and we have shown most clearly in Figure 2 a stamping of generally circular shape comprising a drum portion 7, a circular disc-like portion 8, and a slanting portion 9 which is the indicator dial and is in the shape of a truncated cone extending within the drum portion 7. This hollow stamping we fasten to the disc 6 in any suitable manner, as by brazing or welding, or instead of providing a separate disc and a metal stamping for the indicator dial and drum, we may provide a single stamping which has a central plane portion corresponding to the disc, an obliquely extending portion for the indicator dial in the form of a truncated cone, and a reversely bent portion for the drum, as will be readily understood. All of these parts are in any event joined together so as to move as a unit, and it will be clear that power applied to the drum portion 7 will operate to rotate the rotor shaft. Vernier actuating means are provided comprising in this instance a pulley or spool very much smaller than the drum 7, and connected thereto by suitable power transmitting means.

We have indicated in Figure 1 a bracket 10 joined to the casing of the condenser gang, or to a portion of the base or frame of the radio set. This bracket member extends below the drum 7, and there is attached to it a second bracket member 11 forming interspaced, parallel portions. In these parallel portions we journal an actuator shaft 12 upon which the pulley or spool 13 is fixed. Upon the projecting portion of the shaft 12 where it extends through the front panel or casing of the radio set, we will place the ordinary actuating knob, which, for the sake of clearness, we have not shown in the figures. We connect the pulley 13 with the drum 7 by a motion transmitting means. Reference to Figure 3 will indicate a cable 14 anchored to the drum as at 15 passing around it in a counter-clockwise direction, and around the spool 13 also in a counter-clockwise direction, whence it returns to the periphery of the drum 7 and is held there by a suitable tensioning device. We have shown a bracket 16 attached to the drum and perforated to receive a cotter pin 17, to which the cable is attached. The ends of the cotter pin are bent over as at 17a, and a coil spring 18 bears against the bracket 16 and the turned over ends of the cotter pin, thereby tensioning the band.

The truncated cone portion of the disc and drum assembly is to be our indicating dial, and it is accordingly marked off with proper indicia 9a or covered with printed celluloid so marked, or the like. To the bracket member 11 we attach an upstanding member 19 serving as a face plate. This may have side-wise corrugations 20 for strength. Ordinarily it will be a part of the front panel of a radio set which will be cut out to expose a

central portion of the face plate 19. It also has an elongated perforation indicated at 21 to expose a portion of the dial member. It will be noted that the exposed portion of the dial member is located adjacent to the actuating shaft 12 and that if a knob attached to the said shaft is rotated in a clockwise direction, the exposed portion of the dial will appear to move in the same direction, although the drum portion and the condenser shaft 3 rotate in a counter-clockwise direction. It will be noted also that the indicator opening 21 and the actuating knob are located quite close together, which is an advantage in the construction of radio sets; and further, that inasmuch as the line of sight of an observer is normally directed downwardly toward the exposure opening 21, the dial itself, lying at an angle to the face plate 19, is substantially at right angles to the line of sight of the observer. A pointer 21a is provided in the window 21.

The truncated cone shape of our dial portion provides a central clearance, and in this central clearance we mount a lamp as follows: A bracket 22 extends at right angles to the upper portion of the face plate 19 and bears a depending lamp socket 23, into which an illuminating bulb 24 may be screwed. Suitable current connections to the socket may be made as readily understood. The lamp may be provided with a complete housing, of which the face plate 19 forms a front portion if desired, such a housing being indicated at 25 in Figure 1, and the lower portion thereof will have an aperture corresponding to the aperture 21 in the face plate, whereby the light from the bulb 24 can reach the dial.

In this way we have achieved an exceedingly compact construction which is inexpensive to produce, which assures good illumination of the dial portion and also ready visibility of the dial. It will be noted that only light reflected from the dial will reach the eyes of the observer, and that the illumination bulb is completely concealed. The face plate 19 may have, of course, other configurations or embossed ornamentation, the essential being that it provides an aperture for the inspection of the dial and means to conceal the light itself. Where the face plate is to form a visible part of the external casing of the radio set, it will be finished in a suitable ornamental manner.

Various modifications may be made in our invention without departing from the spirit thereof.

Having thus described our invention, what we claim as new and desire to secure by Letters Patent, is:

1. Controlling and indicating means comprising a shaft, means for rotating said shaft, and a dial member on said shaft, said dial member having an inwardly extending trun-

cated cone shape, a face plate with an aperture for the inspection of a portion of said dial, and a light located behind the front surface of said face plate and above said aperture.

5 2. In controlling and indicating means a shaft to be controlled, a member fixed on said shaft comprising a disc, an outwardly flaring truncated cone portion, and a drum portion, and outside said truncated cone portion an actuator shaft located beyond said drum portion, and a flexible driving connection between said drum portion and said actuator shaft, said flexible driving member arranged 10 to cause said controlled shaft to rotate in the opposite direction to said actuator shaft, a face plate concealing said mechanism, and an aperture in said face plate adapted to expose a portion of said truncated cone adjacent 15 said actuator shaft.

20 3. In controlling and indicating means a shaft to be controlled, a member fixed on said shaft comprising a disc, an outwardly flaring truncated cone portion, and a drum portion, and outside said truncated cone portion an actuator shaft located beyond said drum portion, and a flexible driving connection between said drum portion and said actuator shaft, said flexible driving member arranged 25 to cause said controlled shaft to rotate in the opposite direction to said actuator shaft, a face plate concealing said mechanism, and an aperture in said face plate adapted to expose a portion of said truncated cone adjacent 30 said actuator shaft, and illuminating means behind the front surface of said face plate and adapted to illuminate the visible portion of 35 said truncated cone.

40 4. In a radio set a condenser gang disposed at an angle to the front panel of said set, a rotor shaft therein, an operating member attached to said rotor shaft and comprising a disc non-rotatably mounted thereon, an outwardly flaring truncated cone portion marked off to form a dial, and a drum portion 45 extending outside of said truncated cone portion, mounting means for an actuator shaft beyond said drum, a face plate attached to said mounting means and extending in front 50 of said truncated cone, an actuator shaft rotatably mounted in said mounting, a driving connection between said actuator shaft and said drum, said face plate having an aperture for exposing a portion of said truncated cone adjacent said actuator shaft.

55 5. In a radio set a condenser gang disposed at an angle to the front panel of said set, a rotor shaft therein, an operating member attached to said rotor shaft and comprising a disc non-rotatably mounted thereon, an outwardly flaring truncated cone portion marked off to form a dial, and a drum portion 60 extending outside of said truncated cone portion, mounting means for an actuator shaft beyond said drum, a face plate attached to

70 said mounting means and extending in front of said truncated cone, an actuator shaft rotatably mounted in said mounting, a driving connection between said actuator shaft and said drum, said face plate having an aperture for exposing a portion of said truncated cone adjacent said actuator shaft, a mechanical driving connection between said actuator shaft and said drum whereby said shaft and said drum will move in opposite directions, 75 and a light located behind the front surface of said face plate and adapted to illuminate the visible portion of said truncated cone.

80 6. A face plate for a dished dial comprising a hollow distended portion to extend into the dial, and an extension from said distended portion having a journal opening.

85 7. A face plate for a dished dial comprising a hollow distended portion to extend into the dial, with dial-reading means in one end, and an extension from said end of said distended portion having a journal opening.

90 8. Controlling and indicating means comprising a shaft, an inwardly dished dial member fixed on said shaft, having a substantially cylindrical peripheral part, a drum rotatively mounted near said dial, and a flexible element passing around said drum in one direction, and said peripheral part in the opposite direction.
